(57) CLAIM

We claim the ornamental design for a perforated band for a fitness monitoring capsule, as shown and described.

DESCRIPTION

FIG. 1 is a front view of a perforated band for a fitness monitoring capsule, showing a first band portion separated for clarity of illustration.

FIG. 2 is a rear view thereof.

FIG. 3 is a side view thereof.

FIG. 4 is an opposite side view thereof.

FIG. 5 is a top view thereof.

FIG. 6 is a bottom view thereof.

FIG. 7 is an isometric view thereof.

FIG. 8 is another isometric view thereof.

FIG. 9 is a front view of the perforated band for a fitness monitoring capsule, showing a second band portion separated for clarity of illustration.

FIG. 10 is a rear view thereof.

FIG. 11 is a top view thereof.

FIG. 12 is a bottom view thereof.

FIG. 13 is a side view thereof.

FIG. 14 is an opposite side view thereof.

FIG. 15 is an isometric view thereof.

FIG. 16 is another isometric view thereof; and,

FIG. 17 is a perspective view showing the first and second band portions of FIGS. 7 and 16, respectively, in an environment of use.

The broken lines in the drawings illustrate portions of the perforated band for a fitness monitoring capsule that form no part of the claimed design. The dash-dot-dash lines illustrate a boundary of the claim and form no part of the claimed design. The Fitbit logo and other lettering shown within the dash-dot-dash lines represent environmental subject matter and form no part of the claimed design. The other dotted lines showing the holes on the first band portion of FIGS. 1, 2, 5-8 and 17, and the keeper, tang and buckle on the second band portion of FIGS. 9-17 represent portions of the perforated band for a fitness monitoring device that form no part of the claimed design.
